UNITED STATES PATENT OFFICE.

EDWARD ROBERTI, OF LOS ANGELES, CALIFORNIA.

SPRING-BED.

982,391.

Specification of Letters Patent. Patented Jan. 24, 1911.

Application filed March 3, 1910. Serial No. 547,158.

To all whom it may concern:

Be it known that I, EDWARD ROBERTI, a citizen of the United States, residing at Los Angeles, in the county of Los Angeles and State of California, have invented a new and useful Spring-Bed, of which the following is a specification.

This invention relates to spring beds which are adapted to accommodate two persons, and the main object of the invention is to provide such a bed with means whereby the two sides of the spring bed are rendered more or less independent, so that excessive weight on one side of the bed will not materially affect the other side of the bed. Where two persons of different weights are using a spring bed, the bed tends to sag toward the side where the greater weight is placed, resulting in the inconvenience of the lighter person tending to roll toward the opposite side, and the present invention is directed to obviate this defect.

Another object of the invention is to provide a spring bed of the above described character with means for substantially equalizing the tension or elasticity of the bed throughout its width.

Other objects of the invention will appear hereinafter.

Referring to the drawings:—Figure 1 is a plan of the spring bed; with parts broken away. Fig. 2 is a transverse section on line x^2-x^2 , Fig. 1.

The bed comprises a frame having longitudinal members 1 and cross bars 2 at each end thereof, and a bed spring 3 secured to and stretched between said cross pieces. Said bed spring preferably consists of a woven wire web or fabric having its end portions gripped by suitable clamping means 4 at each end of the bed frame or otherwise secured to the cross members 2. Said bed spring is constructed so as to overlap along the central portion of the bed and this is preferably effected by doubling the woven wire back and forth on itself so as to form two oppositely extending superposed loops or overlap portions indicated at 6, 6' in Fig. 2, said loops or overlap portions 6 overlying the overlap portions 6'.

A reinforcing member consisting of a rope or strand of coiled wire, indicated at 7, extends within each of the loops 6, 6' at the bend thereof so that the bed spring 3 passes over and around one of said ropes and then back over and around the other of said

ropes, then forwardly below the two layers first formed to the other side of the bed, and is secured at its end by the clamping means 4 so as to effectively support the inner 60 end of each loop and to divide the spring bed into two portions 3', 3'', the portion 3' extending over one side of the bed to the bend of the loop 6', and the portion 3'' extending over the opposite edge of the bed 65 to the bend of loop 6.

The triple thickness of web provided at the overlaps or loops 6 together with the reinforcing means 7 provides for considerably greater stiffness at the central portion 70 of the bed than at the side portions, and to equalize, as far as necessary, the stiffness throughout the bed, I prefer to provide additional reinforcing means consisting of longitudinal wires 8 tensioned by coiled 75 springs 9 secured by wires 10 to the respective end members 2. The reinforcing wires 8 preferably extend through the woven wire mesh as indicated in Fig. 2 to enable them to more effectively support the bed. 80

A stiffening rope or reinforcing means consisting of a portion of the width of the spring bed rolled upon itself as shown at 10, and with a core strand 11, is provided at each side of the bed to stiffen the edge 85 thereof.

By reason of the independent support of the two sides 3', 3'' of the bed, by means of the loops 6, 6', each side of the bed may yield more or less independently of the other 90 so that neither of the occupants of the bed is inconvenienced by the depression or sagging of one side of the bed by weight exerted at the other side. At the same time, the reinforcing and separating means at the midwidth of the bed presents such yield or elasticity as not to interfere with the convenient use of the bed as a whole, as would be the case with a solid bar or partition means. The continuity of the bed spring 95 web is of advantage in that, in case of sagging of one side of the bed, no opening is formed through which bed clothes or any part of the occupant's person might protrude. 100

What I claim is:

1. A spring bed comprising a frame, two longitudinal reinforcing members extending between and secured to the ends of the frame near the midwidth of the bed, and a bed spring secured to and extending between the ends of the frame, said bed spring being 110

bent over and around one of said reinforcing members, and then back over and around the other of said reinforcing members, and then forwardly forming two superposed loops with a reinforcing member in the bend of each loop.

2. A spring bed comprising a frame, an elastic fabric secured to and extending between the ends of the frame and folded on 10 itself to form two superposed loops, a reinforcing member extending longitudinally

with the bend of each of said loops, and reinforcing means for said elastic fabric along each side thereof.

In testimony whereof, I have hereunto set 15 my hand at Los Angeles, California, this 23rd day of February, 1910.

EDWARD ROBERT L.

In presence of—

P. H. SHELTON,

FRANK L. A. GRAHAM.
